UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

BINDER DEVICE.

1,267,831.

Specification of Letters Patent.

Patented May 28, 1918.

Original application filed February 2, 1917, Serial No. 146,106. Divided and this application filed September 7, 1917. Serial No. 190,232.

To all whom it may concern:

Be it known that I, GEORGE P. WIGGINTON, a citizen of the United States, residing at the city and county of Kalamazoo, 5 State of Michigan, have invented certain new and useful Improvements in Binder Devices, of which the following is a specification.

This invention relates to improvements in 10 binder devices.

The main objects of this invention are:

First, to provide an improved binder device which facilitates the use of temporary binders or loose sheet holders and particularly those adapted for machine accounting 15 systems.

Second, to provide an improved binder device which facilitates the handling or manipulation of loose record sheets.

Third, to provide an improved binder device which facilitates the handling of temporary binders or loose sheet holders for the manipulation and insertion or removal of the sheets.

Further objects, and objects relating to 25 structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing, forming a 35 part of this specification, in which:

Figure I is a perspective view of a structure embodying the features of my invention.

Fig. II is a vertical longitudinal section 40 of the embodiment of my invention shown in Fig. I with a binder disposed therein.

Fig. III is a detail side elevation with a closed binder disposed in one of the holder members.

Fig. IV is a perspective view of the holder members separated.

Fig. V is an enlarged detail section on a line corresponding to line 5—5 of Figs. II and III.

Fig. VI is a perspective view of another

adaptation of my invention providing a U-shaped binder holder.

Fig. VII is a perspective view of the holder member, shown in Fig. VI, separated.

In the drawing similar reference characters refer to similar parts throughout the several views, and the sectional views are taken looking in the direction of the little arrows at the ends of the section lines.

Referring to the drawing, the binder 60 illustrated is that shown in my Patent #1,174,458, March 7, 1916, and comprises a pair of covers 1, 1, having clamping members 2, 2, pivotally mounted thereon, and binding strips 3 extending between the covers, which are provided with suitable adjusting means whereby the binder members may be retracted and extended, the adjusting means not being shown. The binder constitutes, generally speaking, a pair of 65 separably associated binder members.

The sheets 4 are preferably such as are shown in my said patent but, as they form no part of my present invention, they are not described with further detail herein.

I provide three holder sections or members, designated generally by the numerals 5, 6 and 7, the sections 5 and 7 being adapted to be associated interchangeably with the section 6. This is described in detail in my 80 copending application, filed February 2, 1917, Ser. No. 146,106, of which application this is a division.

The sections or members 5 and 6 are associated to provide the W or double trough-like holder, shown in Figs. I and III, while the sections 6 and 7 are associated to provide a U-shaped holder, as shown in Fig. VI.

The holder member 5 comprises base members 8 disposed on edge and having V-shaped recesses in their upper edges for the side member 9 and end member 10 constituting a binder member or sheet holder adapted to receive one of the binder members with the sheets arranged thereon with 95 their inner ends abutting the end member, as shown in Fig. II. The holder or support member 6 comprises a pair of base members 11 on which a side member 12 is mounted and an adjustable end member 13, 100

the end member 13 being pivoted at 14 to the side member 12. The end member 13 is adapted to be supported upon the base members 8 or to rest upon the base members 11 of the holder 6. The base members 11 are adapted to telescope between the base members 8 and are secured in this relation by the rod 15 arranged through holes 16 in the base members 8 and through holes 17 in plates 18 secured on the inner sides of the base members 11.

The base members 11 are notched or recessed at 11' to engage the blocks 19 on the inner sides of the outer members 8.

15 With the parts adjusted to this position the end member 13 rests upon the inclined surfaces 20 of the base members 8. The end member 10 has longitudinal slots 21 therein, while the end member 13 has longitudinal slots 21' aligned with the slots 21. When the holder members are assembled as shown in Figs. I and II these slots are positioned so that the binding strips 3 may extend through the slots when the binder 25 is arranged in the device with one binder member in each holder, as is shown in Fig. II. This provides a secure connection for the parts and holds them in proper alignment.

30 To facilitate the alining or grouping of the sheets on the binder members I provide sheet guides 22 and 23 with which notches 24 of the sheets may be engaged. These guides are preferably detachably mounted 35 on the end members but, as the details of the mounting form no part of this invention, they are not further described herein.

To provide a U-shaped holder, as shown in Fig. VI, I associate the members 6 and 40 7. The member 7 comprises a pair of base members 25 connected by a cross piece 25' and having tenon-like extensions 26 at their forward ends adapted to fit into the recesses 11', as shown in Fig. VI.

45 The rod 15 is disposed through the plates 18 and these extensions, as shown in Fig. VII.

When associated as shown in Fig. VI, the side member 27 coacts with the side member 50 12 and end member 13 to provide a U-shaped holder when adjusted to the upright position as shown in Fig. VI, or the side 27 may be adjusted to a horizontal position, thus providing a pair of holders. The 55 side member 27 is provided with carriage top braces 28, the side being hinged to the base at 29. The side member 27 is provided with arms 30 which coact with the end member 13 when the side member 27 is adjusted 60 to a horizontal position. This is described in detail and claimed in my said copending application, the same being shown herein in order to better illustrate the adaptability of the member 6.

My improved binder device is advantageous for handling loose sheets independently of loose sheet binders and it greatly facilitates the handling of binders and loose sheets in the keeping of records, especially where it is desired to keep such records on 70 accounting machines, as they are commonly designated. It, however, is of material advantage where the records are to be kept by hand.

I have not illustrated or described all the 75 embodiments or adaptations of my invention which I contemplate, as I believe the disclosure made will enable those skilled in the art to which this invention relates to embody or adapt the same as may be desired. 80

Having thus described my invention, what I claim as new and desire to secure by Letters Patent, is:

1. In a device of the class described, the combination of a holder member comprising a base, and side and end members mounted thereon in coacting relation, the end member being pivoted at its outer edge for adjustment to an outwardly inclined position, and a coacting holder member comprising a base and side and end members mounted thereon in an oppositely inclined coacting relation, said adjustable end member being supported in an outwardly inclined relation when said holder members 90 are operatively associated, and means for detachably connecting the bases of said holder members.

2. In a device of the class described, the combination of a holder member comprising 100 coacting side and end members, the end member being adjustable, and a coacting holder member removably associated therewith and comprising coacting side and end members, said adjustable end member being 105 supported in an outwardly inclined relation when said holder members are operatively associated.

3. In a structure of the class described, the combination of a holder member comprising 110 a base and side and end members mounted thereon in coacting relation, the end member being pivoted at its edge adjacent said side member, and a coacting holder member removably associated therewith, said adjustable end member being supported in an 115 outwardly inclined relation when said holder members are operatively associated.

4. In a device of the class described, the combination of a holder member comprising 120 coacting side and end members, the end member being adjustable, and a removable trough-like holder member removably associated therewith and adapted when associated therewith to support said end member 125 in an outwardly inclined relation.

5. In a device of the class described, the combination of a holder member comprising

ing coacting side and end members, the end member being adjustable, and a coacting holder member detachably associated therewith and constituting means for supporting 5 said adjustable end member in one position.

6. A holder member of the class described comprising a base, a side member mounted thereon, an end member pivoted at its edge adjacent said side member for adjustment to 10 a horizontal position or to an outwardly inclined position, and a coacting holder mem-

ber detachably connected to said base and constituting means for supporting said end member when associated therewith.

In witness whereof, I have hereunto set 15 my hand and seal in the presence of two witnesses.

GEORGE P. WIGGINTON. [L. S.]
